UNITED STATES PATENT OFFICE.

CHARLES A. BAILEY, OF CROMWELL, CONNECTICUT.

DESIGN FOR A TOY SAFE.

SPECIFICATION forming part of Design No. 27,526, dated August 17, 1897.

Application filed May 14, 1897. Serial No. 636,570. Term of patent 7 years.

To all whom it may concern:

Be it known that I, CHARLES A. BAILEY, a citizen of the United States, residing at Cromwell, in the county of Middlesex and State of Connecticut, have invented and produced a new and original Design for Toy Safes, of which the following is a specification, reference being had to the accompanying drawings, illustrating the same, in which—

10 Figure 1 is a view of the front of the safe. Fig. 2 is a view of the right-hand side of the safe. Fig. 3 is a view of the back. Fig. 4 is a view of the top of the safe.

This invention has relation to a certain new 15 and original design for toy safes; and it consists in the novel configuration of parts, as hereinafter described, and illustrated in the accompanying drawings.

Referring to the drawings, the circular door 20 A, Fig. 1, is ornamented with a scalloped border a , and a circular series of small panels a' , arranged around the center of the door and bearing the numbers for the lock combination, a leaf-and-flower figure a^2 being arranged at 25 each side of the door and extending around the centrally-arranged panels. Spaces are left above and below the central panels, as shown, to receive a description or trade-name which may be given to the bank.

30 The corners of the safe front are ornamented with the scalloped design a^3 . The revolving knob-base is ornamented with a scalloped design a^4 and the arrow a^5 , adapted to point to the numbers in the series of panels a' .

35 The front of the safe at each side or edge is ornamented with the waved or scalloped figures a^6 .

The sides of the safe are ornamented precisely alike and as shown in Fig. 2, wherein 40 the rectangular panel B of each side being in-

closed in a scalloped border b and being designed with an outer raised line of small squares b' at each edge and a line of points or dots b^2 within said outer line, as shown. On the lower part of the panel is a curved cornu- 45 copia figure b^3 and scroll-and-leaf figures $b^4 b^5$, while from the cornucopia rises a triple-leaf figure b^6 , and a flower-and-leaf design $b^7 b^8$ extends over the panel to the top thereof, a humming-bird b^9 being at the left center of 50 the panel and a butterfly b^{10} in the right-hand upper corner.

The back C of the safe is designed with a central flower figure c , from between the petals of which radiate leaves c' , which surround 55 the central figure and are in turn inclosed within the elaborate wreath C' of flowers and leaves, as shown. The corners of the back panel are filled by the scalloped and raised figures c^2 , which are further ornamented by 60 the design c^3 . The edges of the panel are ornamented by the waved or scalloped figures c^4 .

The top D of the safe has its panel sunken and surrounded by a curved border d , within which is a leaf-and-flower scroll d' , extending 65 around the rectangular dotted line d^2 . The space within this rectangle is partly occupied by the scalloped and ornamented handle-plate E and handle-recess E', in which the money-opening e is arranged, the corners and remainder of the rectangular space being ornamented with the flower-and-leaf designs d^3 , 70 d^4 , and d^5 , as shown.

What I claim is—

The design for a toy safe substantially as 75 herein shown and described.

CHAS. A. BAILEY.
